UNITED STATES PATENT OFFICE.

ADOLF THYM, OF KATZHÜTTE, GERMANY.

MUD-GUARD FOR CYCLES.

SPECIFICATION forming part of Letters Patent No. 635,614, dated October 24, 1899.

Application filed June 19, 1899. Serial No. 721,108. (No model.)

To all whom it may concern:

Be it known that I, ADOLF THYM, inn-keeper, a subject of the Prince of Schwarzburg-Rudolstadt, residing at Katzhütte, in 5 the Principality of Schwarzburg-Rudolstadt and German Empire, have invented certain new and useful Improvements in Mud-Guards for Cycles, of which the following is a specification.

10 This invention relates to improvements in mud-guards for cycles; and it consists in a novel construction and arrangement of the parts of a flexible mud-guard capable of being detachably secured to the cycle-frame and 15 adapted to be rolled into a small compass when removed from the cycle, so as to be conveniently carried in a pocket or pouch.

The invention consists in features of construction and novel combinations of parts 20 in a flexible and detachable mud-guard, as hereinafter more particularly described and claimed.

In the annexed drawings, Figure 1 is an elevation of a cycle with my improved mud-guard 25 attached thereto. Fig. 2 is a broken plan view of the mud-guard detached. Fig. 3 is a perspective view showing the mud-guard in a rolled condition, so that it can be conveniently carried in the pouch.

30 My improved mud-guard comprises a flexible band-like strip *a*, provided at suitable points with detachable clasps or fastening devices *d* and *f*, provided, respectively, with hooks *b* and eyes *c*, as shown in Figs. 2 and

35 3. The forward end portion *r* is adjustably engaged with the clasp part *f* and is provided with any suitable clip-buckle *S*, so arranged that the flexible band or strip *a* may be easily lengthened or shortened and adjusted to any

40 required length. In the rear portion of the flexible band *a* there is arranged an inflatable tube *h*, having an inflating-valve *i* at one end. By means of any suitable air-pump attached to the valve *i* the tube *h* can be inflated, so as

45 to impart a requisite degree of rigidity to the rear part of the flexible band *a*, whereby the rear portion of the mud-guard will be capable of sustaining itself above the rear cycle-wheel when said rear portion of the mud-guard is 50 attached to the rear portion of the cycle-frame.

On the rear portion of the mud-guard there is a hook *g* to engage a brace *k* on the rear fork *l* of the cycle-frame, as shown in Fig. 1, with the inflated and stiffened portion of the mud-guard projecting above the rear wheel. 55 In attaching this mud-guard to a cycle-frame the hooks *b* and eyes *c* at the forward end of the strip *a* are first disconnected from each other. The clasp *d* is then passed around the front fork *p*, and the hooks *b* and eyes *c* are 60 then again brought into engagement, thereby supporting the forward end of the mud-guard, as shown in Fig. 1. The flexible band or strip *a*, constituting the main portion of the mud-guard, is passed rearwardly beneath the frame 65 of the cycle and upward immediately in rear of a brace *m* on the lower branch *n* of the rear fork. From this point the mud-guard is extended upward and its hook *g* is engaged with the cross-brace *k* of the rear fork *l*, as before 70 mentioned. On the band *a*, intermediate the cross-braces *m* and *k*, there is attached a clasp *f* for engagement with a clasp *d*, passed around the saddle-pillar *t*, as shown in Fig. 1. It will be observed that the clasps *d* and *f* for attaching the band *a* to the saddle-pillar *t* have 75 the same construction as the clasps *d* and *f* for attaching the forward end of the mud-guard to the front fork *p* of the cycle-frame. The mud-guard is easily detached from the 80 cycle-frame by simply disconnecting the clasps *d* and *f* and disengaging the hook *g* from the rear part of the frame. The valve *i* can be opened to deflate the tube *h*, and then 85 the flexible mud-guard can be easily rolled into a compact form, as shown in Fig. 3, the clasps *d* and *f* being first again engaged with each other, as shown. The mud-guard can be very quickly attached to or detached from the cycle-frame, and being composed of any 90 suitable flexible material of sufficient strength it can be easily rolled into small compass after the tube *h* has been deflated.

What I claim as my invention is—

The herein-described detachable mud- 95 guard, consisting of a flexible band or strip *a* provided with fastenings to detachably engage the front and rear portions of the cycle-frame, a buckle for adjusting the length of said band, and an inflatable tube *h* inserted 100

in the rear portion of said flexible band and provided at one end with an air-valve *i*, whereby the said mud-guard can be inflated to impart the requisite stiffness thereto, the said guard being adapted to be rolled into a small compass when deflated, substantially as described.

In testimony whereof I have hereunto set my hand in presence of two subscribing witnesses.

ADOLF THYM.
